UNITED STATES PATENT OFFICE

SAMUEL SEGAL, OF NEW YORK, N. Y.

DISPLAY BOX

Application filed May 4, 1929. Serial No. 360,345.

This invention relates to a display device and aims to provide an article of this character having structurally and functionally improved characteristics over devices of this type as heretofore provided.

It is an object of the invention to furnish a display device, the parts of which will be relatively few in number and rugged and simple in construction, these parts being 10 capable of ready manufacture at a nominal figure, and being, moreover, capable of being assembled to provide an article which will attractively display merchandise and may be used frequently without the necessity 15 of repairs.

Another object of the invention is that of furnishing a display device which will effectively house and protect articles during shipment and by means of which subsequently 20 they may be effectively displayed.

With these and further objects in mind, reference is had to the attached sheet of drawings illustrating practical embodiments of the invention and in which:

25 Figures 1 and 2 are perspective views of a display box and showing the same in their closed and open positions respectively;

Figs. 3 and 4 are fragmentary sectional views of different types of construction which 30 may be employed, and

Figs. 5 and 6 are perspective views of pintles which may form parts of the structure.

In these views reference numeral 10 indicates a receptacle body which is conveniently 35 formed of sheet metal and with which a lid 11 is associated. This lid may likewise embrace a body of sheet metal and be formed with depending flanges 12 overlying the upper edges of the body in order to provide in 40 conjunction therewith a proper joint, guarding against the entrance of foreign matter into the interior of the receptacle.

The receptacle body may—particularly in the instance of cigar boxes—be lined with 45 suitable wood material arranged in the form of sheets or strips 13. With a view to securing the lid to the box part, both of these elements may be formed with hinge portions 14 maintained in operatively association by 50 pintles 15, which extend through the bores of

these portions. These pintles are—as is customary—in the form of pins, and, as shown in Fig. 5, they may terminate in outer offset end portion 16, or as in Fig. 6, in a loop 17, with which a cord 18 is associated.

In use, the pintles are extended through the hinge portions after the lid has been placed in association with the box body. Thereafter, it is obvious that the lid may be swung freely with respect to the body and the latter may be filled with any desired commodity such as, for example, cigars and cigarettes. After the receptacle has been opened for the purpose of dispensing its contents, it may readily be arranged in display position 65 by simply withdrawing the pintles which permits of a detachment of the lid from the box body. Such detachment may be facilitated by the offset ends of the pintles heretofore described, or by the use of the cords also 70 previously referred to. In any event, the lid is now arranged so that its rearmost flange underlies the rear edge of the box body and, in such position of the parts, it will be observed that the openings 19 and 20 formed 75 in the box and lid, respectively, align with each other. Consequently, the pintles may now be employed in order to secure the parts against relative movement, in that with such parts in the position aforementioned, the inner face of the lid will bear against the rear face of the box body to assure this result.

It will be observed that the openings 19 may either be in line with a spaced extent between the liner provided by the strips 13 85 and the inner face of the box body, or if desired, these strips may be recessed as has been indicated at 21, in Fig. 4, in order to accommodate the pins. In either event the desired results of rigidity and effective display, are 90 achieved.

From the foregoing, it will be understood that, among others, the several objects specifically aforescored to, are achieved. It will, moreover, be appreciated that numerous 95 changes in construction and rearrangement of the parts might be resorted to readily, without departing from the spirit of the invention as defined by the claims.

Having described my invention what I 100

claim as new, and desire to secure by Letters Patent, is:

1. A display device including, in combination, a receptacle, a lid, hinge portions forming a part of said lid and receptacle, pintles to extend through the bores of said hinge portions, and said lid and receptacle being each formed with openings to one side of and additional to said bores to receive said pintles, whereby to retain said lid against movement with respect to said receptacle and in a position substantially at right angles to the base thereof.
2. A display device including a receptacle, a lid, hinge portions forming a part of said receptacle and lid, pintles to enter the bores of said hinge portions, said pintles being movable, and said receptacle and lid being each formed with openings to align with each other and to receive said pintles said openings being disposed to one side of the bores of said hinge portions whereby to retain said lid extending at an angle, said receptacle being fixed against movement with respect to the same.
3. A display device including a receptacle, lining material within said receptacle, hinge portions forming a part of said receptacle, a lid to close said receptacle, hinge portions forming a part of said lid, pintles to extend through the bores of said hinge portions, and said receptacle and lid being each formed with openings to one side of said bores and to receive said pintles subsequent to their withdrawal from the bores of said hinge portions, and to retain said lid fixed with respect to said receptacle, the openings in the latter being in a plane beyond the inner face of said lining material.
4. A display device including a receptacle, a lid, a downwardly extending flange forming a part of said lid, hinge portions associated with said lid and receptacle, pintles to enter the bores of said hinge portions to swingingly retain the lid with respect to said receptacle, and the body of the receptacle and flange of said lid being formed with openings to accommodate said pintles subsequent to their withdrawal from the hinge portions, whereby to retain said lid in elevated position and rigid with respect to said receptacle.

In testimony whereof I affix my signature.
SAMUEL SEGAL.
